DESIGN FOR A COMBINED SALT AND PEPPER SHAKER

Howard L. Ross, New York, N. Y.

Application November 12, 1943, Serial No. 111,669

Term of patent 7 years

(Cl. D44—22)

To all whom it may concern:

Be it known that I, Howard L. Ross, a citizen of the United States, residing at New York city, in the county and State of New York, have invented a new, original, and ornamental Design for a combined Salt and Pepper Shaker, of which the following is a specification, reference being had to the accompanying drawing, forming part thereof.

Fig. 1 is a perspective view of a combined salt and pepper shaker, showing my design.

Fig. 2 is a top plan view thereof.

Fig. 3 is a front perspective view of the salt shaker element removed from the remainder of the article.

Fig. 4 is a rear elevational view of the pepper shaker element.

I claim:

The ornamental design for a combined salt and pepper shaker, substantially as shown.

HOWARD L. ROSS.
